UNITED STATES PATENT OFFICE.

JOSEPH SIDNEY COOLIDGE, OF WASHINGTON, DISTRICT OF COLUMBIA.

HARNESS ATTACHMENT.

SPECIFICATION forming part of Letters Patent No. 392,908, dated November 13, 1888.

Application filed September 8, 1888. Serial No. 284,909. (No model.)

To all whom it may concern:

Be it known that I, JOSEPH SIDNEY COOLIDGE, of Washington, in the District of Columbia, have invented certain new and useful Improvements in Harness Attachments; and I do hereby declare the following to be a full, clear, and exact description of the invention, such as will enable others skilled in the art to which it appertains to make and use the same.

10 My invention relates to an improvement in harness attachments, the object of the same being to provide certain improvements over the existing devices for attaching horses to vehicles.

15 A further object is to provide a device of the above character of such construction that the same may be applied to any harness without disfiguring or dismembering the same.

20 A further object in the connection is to provide an adjustable spring-locking bolt.

25 A further object is to provide a device of the above character which shall be simple and economical in construction and durable and efficient in use; and with these ends in view my invention consists in certain features of construction and combinations of parts, as will be hereinafter fully described, and pointed out in the claims.

30 In the accompanying drawings, Figure 1 is a view of the attachment on a horse and thill. Fig. 2 is a sectional view thereof on lines $\alpha\alpha$ of Fig. 1. Fig. 3 is a section of the lug, cap, and bolt. Fig. 4 is a section of the cap-plate. Fig. 5 is a side elevation of the complete device. Fig. 6 is a rear view of the case with the plate removed. Fig. 7 is a front view thereof. Fig. 8 is a section on yy of Fig. 5, and Fig. 9 is a rear view of the case with the plate secured thereon.

35 No. 1 represents a case provided with the downwardly-projecting lips 2. The said lips 2 are provided with the oblong eyes or loops 3 to receive the straps 4 and 5. The case 1 is provided at its rear with the pins 6, which 45 serve to retain the straps 4 and 5 in position by passing through the holes 7, which are preferably made in a series, thereby enabling an easy adjustment of the same when required.

The straps are prevented from rubbing by 50 means of the plate 8, which is removably se-

cured to the case by the screws 9, the said plate neatly fitting over the straps and filling the space occasioned by the projecting lips.

The front of the case 1 is provided with the downwardly-projecting lug 10, in line with 55 which is the cylinder 11, carrying the bolt 12, the free end of which is beveled to facilitate the introduction of the cap to the lug 10. The cylinder is provided at its outer end with the female screw-threads 12 $\frac{1}{2}$, adapted to receive 60 the male thread formed on the thumb-nut 13. The nut is perforated and embraces the bolt 12. The bolt is forced down by means of the spiral spring 14, one end of which bears against the shoulder 15 and the opposite end upon the 65 nut 13. The object of having the bolt removably secured in the cylinder is to enable the spring to be removed when worn without in any manner disfiguring or injuring the cylinder. 70

The plate 16 is secured to the breeching 17 and the trace-strap 18 by means of the screws 18 $\frac{1}{2}$, which are held in position by means of the nuts 19. The said plate 16 is provided at its free end with the annular cap 20, the same 75 sloping downward and adapted to embrace the lug 10, as shown in Fig. 3. The cap is provided with the recess 21 to receive the end of the bolt 12. The plate 16 is provided with the recess 22, adapted to engage the stud 23 on the 80 case 1 for the purpose of steadyng the parts. To the case 1 is secured the spring 24, the office 85 of which is to force the cap from the lug when the bolt is released.

The plate 16 is provided with the loop 25, 85 carrying the tug 26. To the loop 27 of the bolt may be attached the lines 28, as shown in Fig. 2, said lines being connected with the driver by suitable means, so that if the horses should run the tightening of the lines would 90 draw the bolt 12 and the spring 24 would cast the plate 16 aside and release the animal from the vehicle.

It will be observed that the particular advantage this device possesses over others consists in the construction of the case and arrangements of the straps, whereby the same may be attached to any harness without cutting the same, as has heretofore been necessary in order to use devices of this character. 100

My invention is secured to harness in the following manner: The strap 4 is provided at its upper end with a buckle, 29, to receive the saddle-strap 30, and the lower end of the strap 4 is free and provided with holes to receive the buckle 31 on the girth 32. The strap 5 is provided with the buckle 33 to receive the end of the breeching 34, the opposite end of the strap 5 being plain and adapted to be secured to the breast-strap 35 by means of the buckle 36 thereon. The tug 26 is placed on the thill and the trace-strap 18 is secured thereon, as shown in Fig. 1. The horse is put between the thills and the cap 20 is shoved upon the lug 10, thereby forcing backward the bolt 12, which immediately returns when the cap is in position and holds the same securely in place.

Having fully described my invention, what I claim as new, and desire to secure by Letters

20 Patent, is—

1. The combination, with the case having curved projecting lips provided with eyes adapted to receive the straps 4 and 5 and pins secured to said casing to engage said straps, of 25 a serviceable plate, 8, covering said straps and pins, substantially as shown and described.

2. The combination, with the case having curved projecting lips provided with eyes to receive the straps 4 and 5, pins secured to said

easing to engage said straps, a lug formed on the opposite side of said casing, and a spring adjacent to said lug, of a cap to engage said lug and means for retaining the cap upon the lug, substantially as shown and described.

3. In harness attachments, the combination, 35 with the case having a lug secured thereto and a spring adjacent to said lug, of a cap adapted to engage said lug, substantially as shown and described.

4. The combination, with the case having 40 downwardly-projecting lips provided with eyes, straps passing through said eyes, and pins to engage the straps, a lug formed on the case, and a spring adjacent to the lug, of a plate carrying removable trace and breeching 45 straps, a tug secured to said plate, and a cap formed on one end thereof adapted to engage said lug and a spring-bolt on the case to engage the cap, substantially as shown and described.

50 In testimony whereof I have signed this specification in the presence of two subscribing witnesses.

JOSEPH SIDNEY COOLIDGE.
